UNITED STATES PATENT OFFICE.

JOHN LINCOLN GISH, OF SOUTH BEND, INDIANA.

DUPLEX VALVE.

1,405,578.

Specification of Letters Patent.

Patented Feb. 7, 1922.

Application filed March 1, 1919. Serial No. 280,180.

To all whom it may concern:

Be it known that I, JOHN LINCOLN GISH, a citizen of the United States, residing at South Bend, in the county of Saint Joseph 5 and State of Indiana, have invented a new and useful Duplex Valve, of which the following is a specification.

The object of my present invention is to construct a duplex valve comprising an 10 apertured valve-casing enclosing a ball-like main valve and a ball-like relief valve, said relief valve having a stem extending through said main valve and provided with a stop to engage said main valve, in such a manner, 15 that said valve is opened or closed, during one turn, or less, of the operating wheel or handle, and that said duplex valve, is provided with means, thereby, limiting the rolling or toppling-over tendency of said main 20 valve, during the opening or closing of said duplex valve, whereby, the said main valve is kept in its working vertical alinement with its valve-seat.

Fig. 1., is a vertical section of my improved 25 apparatus, showing the duplex valve and the quick operating device in the closed, position.

Fig. 2., is a vertical section of my improved apparatus, showing the duplex valve, and 30 the quick operating device, in the open, position.

Fig. 3., shows the head and swing of the operating cam C., and the movement of the cam-plates, 1., and 2., to the position indicated by, 1', and 2',, during a one half ($\frac{1}{2}$) 35 turn of the operating handle H.

Fig. 4., shows the head and swing of the operating cam C., and the movement of the cam-plates, 1., and 2., to the position indicated by, 1',, and 2',, during one-quarter ($\frac{1}{4}$) 40 turn of the operating handle H.

Like letters and figures of reference, refer to like parts, in the several figures.

In Fig. 1.—I., is the inlet and O., is the 45 outlet to the duplex valve, VC., is the apertured valve casing, cylindrical in form and having its lower section of such a diameter and height, as to receive and engage in a loose running-fit manner, the main valve 50 M.,—surmounting the top of the casing VC., as an integral part, is the upper section, of the casing VC., like-wise cylindrical in form but much smaller in diameter, than the lower said section, so as to receive and engage 55 in a loose running-fit manner, the relief

valve R. The said main-valve M., and the said relief-valve R., are ball-like in form.

The valve-casing V., C., guides and directs the ball-like-main-valve M., in its lateral alinement, with its seat, while the relief-valve-stem A., extending through and engaging the ball-like-main-valve M., guides and directs the ball-like-main-valve M., in its vertical alinement, with its seat, during the reciprocating movements of the valve M., 60 within the valve-casing V., C.

The valve-casing V., C., guides and directs the ball-like-relief-valve R., in its lateral and perpendicular working position, while the relief-valve-stem A., of said valve R., 70 extending through and engaging the ball-like-main-valve M., guides and directs the ball-like-relief-valve R., in its vertical alinement, with its seat, during the reciprocating movements, of the valve R., within 75 the valve-casing V., C.

By such an arrangement and relation of parts the ball-like duplex valve is held in lateral and vertical working alinement with its seat, and in an operating position with 80 its quick operating device.

Should the valve-casing V., C., not serve, as a loose lateral guide, to the ball-like-relief-valve R., in its reciprocating movements, within the valve-casing V., C., as soon 85 as the ball-like-main-valve M., was lifted from its seat, the ball-like-main-valve M., would roll or topple over, to some other inclination, other-wise than a vertical working position, which would place the disc of 90 the ball-like-main-valve M., out of vertical alinement, with its seat, and at the same time carry with it, the relief-valve R., from its vertical working position, thereby causing the cooperating part of the relief-valve-stem A., with the operating shaft S., to 95 become disengaged, and render the valve useless and inoperative.

But it is to be noted, that the valve-casing V., C., does form a lateral and perpendicular working guide, for the ball-like-relief-valve R., therein, and while the ball-like-relief-valve R., has a loose running fit, within the valve-casing V., C., the lateral play, between the valve R., and the inside of casing V., C., is not of such a degree, as would allow the ball-like-main-valve M., to roll or turn, from its vertical working alinement, with its seat. Or to set forth the special feature in other words,—the duplex 110

valve herein described is provided with an apertured valve-casing VC., enclosing a ball-like main valve M., and a ball-like relief valve R., said relief valve R., is provided with an apertured stem A., extending through the ball-like main valve M., and having a stop for engaging said main valve M.

Since the main valve M., is spherical in form, and not having any fixed or rigid connection, either above or below its valve-seat, to hold said main valve M., in its upright working position, it is necessary, to provide means, whereby, the ball-like main valve M., may be kept in its upright working position, and not allowed, to roll from or topple over, from its vertical alinement with its seat, during the opening or closure of said duplex valve.

The special feature is provided for, by enclosing the said ball-like relief valve R., provided with its apertured stem A., within the valve-casing VC., in a loose running fit manner, yet sufficiently close to the inner wall of valve-casing VC., so that, if the ball-like main valve M., starts to roll from or topple over, from its vertical alinement with its seat, the said ball-like relief valve R., contacts the inner wall of casing VC., and limits the roll or toppling over tendency of said ball-like main valve M., during the opening or closure of said duplex valve, thereby, keeping the ball-like main valve M., in vertical alinement with its seat, and at the same time holding the coöperating means, at the outer end of stem A., in working alinement with its operating means, thereby, allowing the duplex valve to be opened or closed.

R., is the relief valve; M., is the main valve; A., is an apertured relief valve stem; B., B',, B'',, is the valve body; P., is the cam-plates, 1., and 2., joined together by the standard 3., and coupled to the apertured relief valve stem A.; C., is the operating cam; S., is the operating cam shaft; S., B., is the cam shaft bearing; G., is a groove on cam shaft for lubricants; D., is a gland valve disc, on cam shaft, to prevent leakage, between cam shaft S., and cam shaft bearing S., B.; s., is a stop on cam shaft bearing S., B.; s', is a stop on operating handle H.; H., is the operating handle; O., O', O'',, is the inlet, passage-way, and outlet, through the stem A.

In operation, the operating handle H., actuates the cam shaft S., which in turn revolves the cam C.

In opening the valve, the cam C., contacts the cam-plate, 1.

The cam-plates 1., and 2., being coupled, to the apertured relief valve stem A., the said stem is correspondingly actuated as the cam C., is revolved, whereby, the duplex valve is opened.

(See my prior patent No. 1042547, for duplex valve).

In closing the valve, the cam C., contacts the cam-plate 2., and as the cam C., is returned to its starting position, a corresponding action is imparted to the aperture relief valve stem A., thereby returning the duplex valve, to its valve seats, whenever, so desired.

What I do claim as my invention, and desire to secure, by Letters Patent is,—

1. In a duplex valve comprising an apertured valve-casing enclosing a ball-like main valve and a ball-like relief-valve, said relief-valve having a stem extending through said main valve and provided with a stop to engage said main-valve, a circumferential guide for said main-valve, forming a part of said casing said relief-valve contacting in a loose running fit, with the inner wall of said guide, during the reciprocating movement of said relief-valve, thereby limiting the rolling or toppling-over tendency of said main-valve, during the opening or closing of said duplex valve, whereby, the said main-valve is kept in its working vertical alinement, with its valve-seat.

2. In a duplex valve comprising an apertured valve-casing enclosing a ball-like main-valve and a ball-like relief-valve, said relief-valve having a stem extending through said main-valve and provided with a stop to engage said main-valve, a circumferential guide, for said relief-valve, forming a part of said casing said relief-valve contacting in a loose running fit, with the inner wall of said guide, during the reciprocating movement of said relief-valve, thereby limiting the rolling or toppling-over tendency, of said main-valve, during the opening or closing of said duplex valve, whereby, the said main-valve is kept in its working vertical alinement, with its valve-seat, and whereby, the coöperating parts, at the outer end of said relief-valve-stem, are maintained in working alinement, with its operating means, allowing the duplex valve to be opened or closed.

In testimony whereof, I have signed my name, to this specification, in the presence of two subscribing witnesses.

JOHN LINCOLN GISH.
